UNITED STATES PATENT OFFICE.

JOHN MCGRATH, OF NEW YORK, N. Y.

FOLDING TABLE.

SPECIFICATION forming part of Letters Patent No. 299,241, dated May 27, 1884.

Application filed October 8, 1883. (No model.)

To all whom it may concern:

Be it known that I, JOHN MCGRATH, of the city, county, and State of New York, have invented a new and useful Improvement in 5 Folding Tables, of which the following is a full, clear, and exact description.

Reference is to be had to the accompanying drawings, forming a part of this specification, in which similar letters of reference indicate 10 corresponding parts in all the figures.

Figure 1 is an under side view of my improved folding table, partly folded. Fig. 2 is a sectional side elevation of the same in position for use. Fig. 3 is a sectional end elevation of the same, taken through the broken line *x x*, Fig. 1. Fig. 4 is a sectional elevation of a part of the same, taken through one of the bracket-bearings.

The object of this invention is to provide 20 tables constructed in such a manner that they can be compactly folded for storage and transportation, and when opened for use will be firm and rigid.

The invention consists in a folding table 25 constructed with a table-top provided with hinged legs connected in pairs by cross-bars, and held in place by spring-pressed brackets constructed to engage with lugs attached to the said cross-bars and legs, so that the said 30 legs will be held securely when folded and when unfolded, as will be hereinafter fully described.

A is the table-top, which is formed of three or more layers of veneer, glued to each other 35 with the grain of one layer crossing the grain of the adjacent layer or layers. The top A, at its edges, is attached to a frame, B, and is strengthened by longitudinal or cross bars C, attached to it and to the said frame B. With 40 this construction the table-top can be made very light while having the requisite strength.

To the under side of the table-top A B C, near each end, is hinged a pair of legs, D, which are connected by a cross-bar, E, so that 45 the said legs will move together. The cross-bar E of one pair of legs D is made shorter than the cross-bar of the other pair, so that one pair of legs will fold down between the legs of the other pair.

To bearings F, attached to the under side of 50 the table-top A B C, are hinged brackets G of the brace-arms H, which are provided with long cross-rods I, pivoted to bearings J, also attached to the table-top. The outer end of each bracket G has a catch, K, made with a 55 beveled end and a square shoulder formed upon or attached to it, and projecting in such a direction as to cross the edge of the cross-bar E when the legs D are unfolded and the said bracket turned up to engage with a lug, 60 L, attached to the said edge of the cross-bar to hold the said legs in place. The legs D are held in place, when folded, by a catch, M, attached to the cross-rod I, and which, when the brackets G are turned down, engages with 65 the lug L, as shown in the left-hand part of Fig. 1. The hinged ends of the brackets G are made square and rest against springs N, placed in recesses in the bearings F, and which are made of sufficient strength to hold the said 70 brackets securely in place when turned up and when turned down.

To bearings O, attached to the table-top A B C, are hinged brackets P, which are made with an offset, as shown in Figs. 1 and 2, so 75 as to pass beneath the cross-bars E, as shown in Figs. 1 and 2. The brace-arms Q of the brackets P are provided with cross-rods R, the ends of which are pivoted to bearings S, attached to the table-top. The outer ends of 80 the brackets P are slotted to engage with lugs T, attached to the legs D, as shown in Figs. 1, 2, and 3, and thus assist in holding the said legs in place when unfolded. The ends of the brackets P are made square, and rest upon 85 springs U, placed in recesses in the bearings O, to hold the said brackets in place when turned up and when turned down. In the case of small tables the brackets P will not be required, the brackets G being sufficient to hold 90 the legs D in place. In unfolding the table the brackets G are turned up to withdraw the catches M from the lugs L. The legs D are then unfolded, and as they come into position the catches K engage with the lugs L automatically, and thus fasten the said legs in 95 place. When additional security is required, the brackets P are turned up to cause their

slotted ends to engage with the lugs T. The table is folded by turning down the brackets P, releasing the catches K from the lugs L, folding down the legs D, and then turning 5 down the brackets G, causing the catches M to engage with the lugs L, and thus fasten the folded legs in place.

Having thus described my invention, I claim as new and desire to secure by Letters Patent—
10 The combination of the table-top A, having

hinged legs D, cross-bars E, and lugs L on said cross-bars, with the folding brackets G H I, bearings F J, springs N, and the catches K M for engaging said lugs L to hold the hinged legs either in their folded or unfolded positions, 15 substantially as set forth.

JOHN McGRATH.
